UNITED STATES PATENT OFFICE.

JOHN HERMAN HUNT, OF DAYTON, OHIO, ASSIGNOR TO THE DAYTON ENGINEERING LABORATORIES COMPANY, A CORPORATION OF OHIO.

ENGINE-STARTER SYSTEM.

1,231,362.

Specification of Letters Patent. Patented June 26, 1917.

Application filed September 3, 1914. Serial No. 859,968.

To all whom it may concern:

Be it known that I, JOHN HERMAN HUNT, residing at Dayton, county of Montgomery, and State of Ohio, have invented certain 5 new and useful Improvements in Engine-Starting Systems, of which the following is a full, clear, and exact description.

This invention relates to an improvement in electrical systems for internal combustion 10 or explosion engines, and more particularly to systems of this type wherein an electric machine is driven as a generator, or is operable as a motor for starting purposes.

One of the objects of the present invention 15 is to provide a special planetary gearing between the electric machine and the combustion engine, which is to be brought into use when the machine is operating as a motor for starting purposes, so as to effect a partial reduction in speed between 20 the armature shaft and the engine crank shaft, and also to facilitate the use of a friction or other efficient drive between the flywheel and an element actuated by the 25 motor.

A further object of the present invention relates to a means for controlling the connection between the electric machine and the engine, both when the machine is operating 30 as a motor and also as a generator.

More specifically, the controlling means is 35 capable of a plurality of operations, preferably arranged in progression. Thus an initial movement of the main operating member will lock or so brake certain of the elements of the planetary gearing that a speed reducing gear is established, whereby when the starting device is operating as a motor, the engine will be cranked at a much 40 slower speed than the speed of the motor. The next movement of the main operating member causes the entire planetary gearing, together with the locking or braking assembly, to be oscillated so as to bring a pinion 45 or friction member, which forms a part of the gearing, into engagement or contact with the flywheel or any suitable part of the engine.

Further objects and advantages of the 50 present invention will be apparent from the following description, reference being had to the accompanying drawing, wherein one preferred form of the present invention is clearly illustrated.

In the drawings:

Figure 1 is a fragmentary top plan view 55 of an automobile chassis, and engine including one form of the present invention.

Fig. 2 is a detail view of the controlling mechanism included in the present invention. 60

Fig. 3 is an end view of the planetary gearing.

Fig. 4 is a side view of the structure shown in Fig. 3, with the exterior casing 65 shown in section for the sake of clearness.

Referring to the drawings, the side frames of the chassis are indicated by the numeral 20. Between these frames and upon cross members 21, the engine 22 is suitably mounted. This engine may be of any preferred type, the one shown in the drawing being 70 of the four cylinder, four cycle type, and is shown for the purposes of illustration only and is not to be considered in any way as a 75 limitation of the invention.

The starting device 24 comprises an electric machine which is mounted adjacent to the engine, and so arranged that one end of the armature shaft 25 is provided with a 80 sprocket wheel 26, which is adapted to be connected with a sprocket wheel 27, by means of a flexible shaft or belt 28. The sprocket wheel 27 may be mounted directly 85 on an extension of the crank shaft 29, or on any other shaft which may be connected with the crank shaft or driven thereby in any suitable manner. The armature shaft 25 also has an extension at its other end, as at 30, the extreme end of which forms 90 one part of the universal coupling, as at 32. A driven shaft 33, which is connected to the element 34, forming the other part of the universal joint, carries at one end a 95 suitable pinion 36, which is adapted to engage with the three large pinions 37 of the planetary gearing.

This planetary gearing comprises a casing 40 and three sets of pinions 37, each set being mounted upon the casing 40. Each 100 of the sets of pinions 37 comprise one large pinion 41 and a small pinion 42, the small pinion engaging with a spur gear 45, which is made fast to the brake shaft 46. This 105 brake shaft carries at its extreme rear end a casing 47, about which the friction brake band 48 is placed, and is operated by means of the member 49, in such a manner as to

render the pinion 45 stationary, relative to the other pinions forming the planetary gearing.

The casing 40 is provided with an extended collar 55, which carries the friction roller 56, so that any rotation of the casing 40 will effect a consequent rotation of the friction driving element or roller 56.

This entire assembly, that is, the shaft 33, casing 40, roller 56 and the brake drum 47, are so mounted upon the lever 60, that upon movement of the controlling element 49, this entire assembly will be shifted into such position as to bring the friction roller into contact with the flywheel of the engine. This position will be maintained until the starting operation has been completed.

However, the controlling element 49 is so arranged that upon an initial movement thereof, the brake band 48 will first be pulled tight over the drum 47, whereby the shaft 46 and its pinion 45 will be prevented from turning.

This arrangement is effected by means of the straight arm lever 65, which is fulcrumed at the point 66. This lever has the controlling element 49 and one end of the brake band fastened at its one extremity, while the opposite end of the brake band is fastened at the other end of the lever 65, as at 67.

From the above description, it will be seen that the lever 49 has a progressive action. That is, the complete operation of said lever 65 performs a multiplicity of functions, the first one of which is to tighten up the brake band in such a manner as to lock the shaft 46, and the second operation is to carry the entire gear mechanism into such position that the friction element will engage the flywheel for starting purposes.

As soon as the engine has become self-actuating, the lever 49 is released and under the influence of the spring 68, the assembly comprising the shaft 33, casing 40, roller 56 and the brake assembly, will move back into its normal position. This movement of the parts mentioned above will be stopped by means of the projection 69, which will engage with the shoulder 70, formed on the lever 60.

Of course, as soon as the engine becomes self-actuating, it will immediately start to drive the electric machine 24 as a generator through the sprocket 27, belt 28 and sprocket 26, through the shaft 25.

While I have shown and described one preferred embodiment of the present invention, I reserve the right to make whatever changes or alterations in the construction and combination of the various elements and

parts comprising the present invention, and also the location and arrangement thereof, as may come within the scope of the appended claims.

What I claim is as follows:

1. In a starting device, the combination with an internal combustion or explosion engine; of an electric machine operable as a motor for starting purposes, a planetary gearing between the one end of the electric machine and the engine; and means for moving said planetary gearing into and out of driving connection with the engine for starting purposes.

2. In a starting device for internal combustion or explosion engines, the combination with a power unit; a planetary gearing between said power unit and the engine; an operating member for initially rendering said planetary gearing operable as a speed reduction device and finally connecting the planetary gearing in operative relation to the engine to be started.

3. In a starting device, the combination with an internal combustion or explosion engine; of an electric machine operable as a motor for starting purposes; a planetary gearing including a frictional element between the electric machine and the engine; and means for moving said frictional element into driving engagement with the engine.

4. In a starting device, the combination with an internal combustion or explosion engine; of an electric machine operable as a motor for starting purposes; a planetary gearing connected by a universal joint with the electric machine; and means for shifting the planetary gearing through said universal joint into driving engagement with the engine.

5. In an engine starting device, the combination with a starting device therefor comprising a dynamo electric machine operable as a motor for starting purposes; a planetary gearing having a universal joint connection with the electric machine and shiftable into and out of driving engagement with the engine; and a common operating member capable of an initial operation to render said planetary gearing operable as a speed reduction device, and of a further movement to shift the planetary gearing into operative driving relation to the engine for starting purposes.

In testimony whereof I affix my signature in the presence of two subscribing witnesses.

JOHN HERMAN HUNT.
